[57] CLAIM

The ornamental design for a front face of a light metal wheel, as shown and described.

DESCRIPTION

FIG. 1 is a front view of a front face of a light metal wheel according to our novel design; and,
FIG. 2 is a frontal perspective view of a front face of a light metal wheel according to our novel design.

The logo, screws, and valve illustrated by broken lines in the figures indicate environmental structure only and does not form any part of the claimed design.
